UNITED STATES PATENT OFFICE.

WILLIAM C. BROWN, OF SYRACUSE, NEW YORK, ASSIGNEE TO HUMPHREY GAS PUMP COMPANY, A CORPORATION OF NEW YORK.

IGNITION CONTROL.

1,224,356.

Specification of Letters Patent.

Patented May 1, 1917.

Application filed December 21, 1911. Serial No. 667,190.

To all whom it may concern:

Be it known that I, WILLIAM C. BROWN, a citizen of the United States, residing at Syracuse, in the county of Onondaga, State of New York, have invented a new and useful Ignition Control, of which the following is a specification.

My invention relates to ignition control. My object is to provide improved method and apparatus for effecting electrical ignition of combustible charges.

My invention comprises method and means for utilizing the flow or pressure of liquid in a play pipe or discharge pipe to maintain, against a resisting force, an open electric circuit, until the occurrence of a diminution, cessation, or reversal of said pressure, whereupon the circuit is closed and opened again.

20 Referring to the drawings, which illustrate, by way of example, suitable apparatus for effecting my invention,

Figure 1 is a diagrammatic sectional view of an internal combustion pump employing my improved means for ignition control.

Fig. 2 is an elevation in part section showing my improved means in detail.

Fig. 3 is an elevation in detail, showing the contacts in position different from that shown in Fig. 2.

Fig. 4 is a longitudinal transverse section on line 4—4 of Fig. 2.

Fig. 5 is a vertical section showing additional means for breaking the circuit by the operation of the exhaust valve.

Fig. 6 is a detail in vertical section, on an enlarged scale of said second circuit breaking means.

Similar numerals refer to similar parts throughout the several views.

My invention is especially applicable to internal combustion engines, pumps and compressors of the general type which are now known in the art as the Humphrey pump or compressor. One of the simplest forms of such a pump comprising a combustion and expansion chamber connected with a play pipe, and a discharge, and also connected with a source of liquid supply. The operation of this device, consists in expanding a compressed combustible charge in an expansion chamber against a column of liquid, thereby driving the liquid from the

expansion chamber along the play pipe 55 either to a greater head or pressure. When the momentum of the outward stroke of the liquid is spent the column returns in the play pipe in response to the head or pressure to which it has been driven, and 60 liquid flows back into the combustion chamber to expel burnt products and to compress a fresh combustible charge which has been introduced into said chamber.

In order to secure a maximum efficiency 65 of expansion of the combustible charge, it is important that the charge be ignited at the moment, or very close to the moment, of its maximum compression, and as the amount of compression may vary with each 70 instroke of the liquid, due to a number of conditions which it has been found difficult positively to regulate, it follows that the ignition device should be purely automatic to cause the spark just before the incoming or inflowing column of fluid has come 75 to rest, which time is, of course, the moment of maximum compression.

Referring to the drawings, 5 indicates the combustion chamber with suitable intake for 80 expandible charges and suitable exit for burnt products. 6 indicates a source of supply with which the play pipe or discharge pipe 7 is connected, said connection being controlled by the non-return valve 8. 85 Upon expansion of the charge in chamber 5 the liquid is carried downwardly and along the play pipe 7 and upwardly to the high level tank 9. The momentum of the moving column serves to entrain fresh liquid from 90 the source of supply 6 through the non-return valve 8. Fresh combustible charge may also be entrained during this outstroke. When the momentum of the outstroke is spent the liquid returns, due to the head 95 or pressure to which it has been driven, and flows in the reverse direction, that is, toward the combustion chamber, rising in the combustion chamber to expel burnt products and to compress the fresh expandable charge.

It is this instroke movement or pressure that is now utilized to control the ignition of the compressed combustible charge.

As will be seen by an examination of Fig. 105 2, the spoon shaped paddle or vane 10, is mounted in a suitable housing 11, on the

- spindle 12. This spoon shaped paddle or vane 10 projects into the play pipe 7 as shown in Figs. 1 and 2, with a concave face toward the inflowing water. The spindle 12 passes through a suitable stuffing box and carries on its outer end the arm 13. The arm 13 is provided at its outer end with the binding post 14 and movable contact 15. The contact spring or blade 16 is also secured to 5 and carried by, but insulated from, arm 13. This spring 16 is adapted under certain conditions to engage with contact 15. The housing 11 is provided with a bracket 17 for supporting at its outer end the adjustably secured fixed contact 18, adapted under certain conditions to engage with the contact leaf 16. The bracket 17 also supports or carries the tubular housing 19 for receiving the spring 20 and for carrying the adjustable 10 screw head 21, which, with the coöperating screw 22, supports the upper end of spring 20. Spring 20 is connected at its lower end with the lever or arm 13.
- The operation is as follows: Upon the 15 return stroke of the liquid column toward the expansion chamber, the pressure of the liquid against the concave side of paddle or vane 10, moves it toward the right, that is, toward the expansion chamber, which consequently results in moving the lever 13 and the spring 16 downwardly or in a counter-clockwise direction, against the resistance of the spring 20, thus holding the resilient contact element 16 away from the fixed contact 18. Immediately upon the diminution of 20 flow of the inward stroke of the liquid, or upon the cessation of the same, or upon the reversal of flow, as the case may be, and which will be due to the tension of spring 20, the vane 10 moves in the opposite direction, in response to said spring tension, which results in moving the lever 13 upwardly, causing contact blade 16 to engage with the contact 18 while said blade is still 25 in contact with contact point 15. This results in completing the circuit of a suitable 30 sparking device. Arm 13 continues to move upwardly, in response to spring 20, whereupon point 15 separates from blade or flexible contact element 16, thus again immediately 35 breaking the circuit, so that the make of the circuit is only momentary, thus preventing an undesirable continuation of 40 sparking.
- It will thus be seen that, by a proper adjustment of the tension of the spring 20, which opposes the liquid impelled movement of vane 10, it is possible to provide that the vane may be returned to initial position 45 slightly before the liquid comes to rest in its instroke, so that the spark may be secured slightly in advance of the moment of maximum compression or practically simultaneously therewith; or, by a different adjustment of said spring tension, it may be pro-

vided that the vane shall not move in the opposite direction from the instroke, until after the liquid has come to rest, thus delaying the spark until after the moment of maximum compression. This range of adjustment makes it possible to secure the spark at the moment most suitable to the peculiar conditions which it may be desired to meet.

As above pointed out the spring contact 16 will bridge the contact points 15 and 18 just prior to the arm 13 moving into the position shown in Fig. 3, which is at the end of the compression stroke, and when the ignition takes place. This contact spring 16 will also bridge the contacts 15 and 18 in returning to the position shown in dotted lines in Fig. 2, that is, at the beginning of the instroke.

In order to save unnecessary expenditure of electric current, and also, as a factor of safety, it is often desirable to eliminate this intermediate sparking. This may be done in a number of ways, but I have found that the means shown in Figs. 5 and 6 have been entirely satisfactory. It not only prevents the sparking on the idle stroke, but also prevents ignition if for any reason the exhaust valve does not close.

The wiring shown in Fig. 5 is somewhat different from that shown in Fig. 1, that is to say, the circuit includes the binding post 14, the contact 15, the bridge 16, the contact 18, the binding post 23, the contact 26 and binding post 27 mounted on the spring 28 insulated from the supporting structure the binding post 30 which is secured to the exhaust casing 29. The circuit then includes the two terminals of the spark plug, the usual battery and coil. It will thus be seen that when the exhaust valve 24 is in the closed position as shown in Fig. 5, the valve rod 25 contacts with contact 26 and closes the circuit at this point. This exhaust valve is ordinarily closed by the impact of the water toward the end of the return or compression stroke in the combustion chamber. The exhaust valve is normally otherwise held open by the pressure of spring 31 between the top of the exhaust casing 29 and the collar 32 secured to rod 25. When the exhaust valve is in the open position, rod 21 is depressed as indicated in Fig. 6, breaking contact with the contact member 26. It will thus be seen that in order to produce a spark by the bridging of the contacts 15 and 18, it is necessary that at the same time the exhaust valve 24 be closed in order to close the circuit at the contact 26.

I do not confine myself to the form of vane or paddle shown in the drawings, as in many cases a flat paddle will give satisfactory results. Nor do I limit myself to the particular method of mounting the paddle shown, as obviously many different ways

of mounting the vane or blade, and of utilizing its deflector may be equally within the scope of my invention.

What I claim is:

- 5 1. The method which consists in reciprocating a column of liquid of sufficient bulk and path of travel to acquire useful momentum, said column adapted to move with varying force, projecting into the path of travel of said liquid column a movable element, subjecting said movable element to the influence of a substantially constant force, so that said constant force will sometime cooperate with the force of the moving column and sometimes oppose it, and the said movable element will be controlled by the stronger of said two opposing forces. 70
- 10 2. Means for effecting the electrical ignition of a combustible charge, comprising an electric circuit, fixed and movable contacts therein, a vane projecting transverse the path of travel of a liquid, and supporting means for the movable contact having operative relation with the vane. 75
- 15 3. Means for effecting the electrical ignition of a combustible charge, comprising an electric circuit, fixed and movable contacts therein, a vane pivotally mounted and projecting transverse the path of travel of a liquid, and supporting means for the movable contact having operative relation with the vane. 80
- 20 4. Means for effecting the electrical ignition of a combustible charge comprising an electric circuit, fixed and movable contacts therein, a vane projecting transverse the path of travel of liquid, and spring controlled supporting means for the movable contact having operative relation with the vane. 85
- 25 5. Means for effecting the electrical ignition of a combustible charge, comprising an electric circuit, fixed and movable contacts therein, a vane projecting transverse the path of travel of liquid, and adjustable spring controlled supporting means for the movable contact having operative relation with the vane. 90
- 30 6. Means for effecting the electrical ignition of a combustible charge, comprising an electric circuit, fixed and movable contacts therein, a vane projecting transverse the path of travel of liquid, supporting means for the movable contact having operative relation with the vane, and means for adjusting the fixed contact. 95
- 35 7. Means for effecting the electrical ignition of a combustible charge, comprising an electric circuit, fixed and movable contacts therein, a vane projecting transverse the path of travel of liquid, supporting means for the movable contact having operative relation with the vane and a resilient conducting element for momentarily bridging the fixed and movable contacts during the movement of the latter. 100
- 40 8. Means for effecting the electrical ignition of a combustible charge, comprising an electric circuit, fixed and movable contacts therein, a vane projecting transverse the path of travel of liquid, supporting means for the movable contact having operative relation with the vane, and a flexible contact element for securing momentary electrical connection between the movable and fixed contacts. 105
- 45 9. The combination of an expansion chamber, a play pipe for liquid connected therewith, an electric circuit, fixed and movable contacts in said circuit, a housing connected with the play pipe, a vane mounted in the housing and having its free end projecting into and transverse the path of travel of the liquid in the play pipe, a spindle connected with the vane carrying a movable contact supporting arm, and a flexible contacting element secured to said supporting arm for a momentary contact between the fixed and movable contacts during the travel of the vane. 110
- 50 10. The combination of an expansion chamber, a play pipe for liquid connected therewith, an electric circuit, fixed and movable contacts in said circuit, a housing connected with the play pipe, a vane mounted in the housing and having its free end projecting into and transverse the path of travel of the liquid in the play pipe, a spindle connected with the vane carrying a movable contact supporting arm, a flexible contacting element secured to said supporting arm for a momentary contact between the fixed and movable contacts during the travel of the vane, and a spring connected between a fixed point and the movable contact arm. 115
- 55 11. The combination of an expansion chamber, a play pipe for liquid connected therewith, an electric circuit, fixed and movable contacts in said circuit, a housing connected with the play pipe, a vane mounted in the housing and having its free end projecting into and transverse the path of travel of the liquid in the play pipe, a spindle connected with the vane carrying a movable contact supporting arm, a flexible contacting element secured to said supporting arm for a momentary contact between the fixed and movable contacts during the travel of the vane, and an adjustable tension spring connected between a fixed point and the movable contact arm. 120
- 60 12. Means for effecting electrical ignition of combustible charges, comprising an electric circuit, having two sets of fixed and movable contacts therein, a vane projecting transverse the path of travel of a liquid, supporting means for the one movable contact having operative relationship with the vane. 125
- 65 13. The combination of an expansion chamber with suitable inlet and exhaust valves, a play pipe for liquid connected with 130

the expansion chamber, an electric circuit having two sets of make and break devices, a movable member affected by the flow of liquid in the play pipe for controlling one make and break device and means whereby the exhaust valve controls the other make and break device.

14. The combination of an expansion chamber with suitable inlet and exhaust valves, a play pipe for liquid connected with the expansion chamber, an electric circuit having two sets of make and break devices, a movable member affected by the pressure of liquid in the play pipe for controlling one make and break device and means whereby the exhaust valve controls the other make and break device.

15. The combination of a movably supported body projecting into and transverse the path of travel of a liquid, means for normally counterbalancing the force of liquid

flow against the said body and a motor controlling device adapted to be actuated by said movably supported body.

16. The combination of a pivotally supported body projecting beyond its pivot support into and transverse the path of travel of a body of liquid, means for normally counterbalancing the force of liquid flow against the said body and motor controlling means in operative relationship with said pivoted body.

17. The combination of a movably supported body projecting into and transverse the path of travel of a liquid, means for normally counterbalancing the force of liquid flow against the said body and ignition means controlled by said pivoted body.

WILLIAM C. BROWN.
